Charles R. M. Pohle

United States Patent Office.

CHARLES R. M. POHLE, OF RICHMOND, VIRGINIA.

Letters Patent No. 77,316, dated April 28, 1868.

IMPROVEMENT IN ENVELOPES.

The Schedule referred to in these Letters Patent and making part of the same.

TO ALL WHOM IT MAY CONCERN:

Be it known that I, CHARLES R. M. POHLE, of the city of Richmond, county of Henrico, and State of Virginia, have invented a new and improved Mode of Constructing a Paper Envelope, to be called "The Security-Envelope;" and I do hereby declare that the following is a full and exact description thereof, reference being had to the accompanying drawings, and to the letters of reference marked thereon.

I will now proceed to describe its construction and operation.

Figure 1 represents the paper cut into the shape required for making the envelope, (any size.) The red marking represents the gum, and the blue lines represent the cuts in the paper.

Letter X is the inside of the front part. Letter b is the key-wing. Letter d is the key. Letter a is the lock-wing. Letter c is the door-flap. Letter e is the closing-flap. Letter f is the seal-flap.

First Operation.

Part 1. Take the ready-cut paper as represented in fig. 1, lay down the key-wing b to the inside of the front part X, and raise the key d so that it stands upright, (see Figure 2.)

Part 2. Moisten the gum on the lock-wing a, and put the key d, with your right hand, into the cut of the lock-wing, smooth the lock-wing down, and leave the key d standing upright, as in the first part, (see Figure 3.)

Part 3. Moisten the door-flap c, and smooth it down to the wings a and b, so that the key d stands upright in the opening of the door-flap c, (see Figure 4, representing the envelope ready for use.)

Second Operation.

Part 1. Moisten the gum on the closing-flap e, put the key d through the cut of the closing-flap, and press the flap down well, particularly on its gummed part, (see Figure 5.)

Part 2. Moisten the gum on the key d, and press it down to the closing-flap e, facing the seal-flap f, (see Figure 6.)

Part 3. Moisten the gum on the seal-flap f, and press it down well to the key d, covering the key and the end of the closing-flap, (see Figure 7, representing the envelope closed.)

What I claim as my invention, and desire to secure by Letters Patent, is—

The manner I connect the different parts, and close the whole.

CHARLES R. M. POHLE.
